UNITED STATES PATENT OFFICE.

LOUIS C. RODIER, OF SPRINGFIELD, MASSACHUSETTS, ASSIGNOR TO SAMUEL NORRIS, OF SAME PLACE.

IMPROVEMENT IN BIT-HOLDERS FOR BIT-STOCKS.

Specification forming part of Letters Patent No. 44,047, dated August 30, 1864.

To all whom it may concern:

Be it known that I, LOUIS C. RODIER, of Springfield, in the county of Hampden and State of Massachusetts, have invented certain new and useful Improvements in Bit Stocks or Holders; and I hereby declare that the following is a full, clear, and exact description of the same.

According to the ordinary construction of bit-holders they can only be operated by imparting to them rotary movement continuously in one direction to cause the tool to penetrate the wood or other material which is to be cut or perforated. In many instances it is difficult, if not impossible, to use such implements for the want of space within which the crank of the holder is to be rotated.

To construct a bit-holder which can be operated in contracted spaces—*i. e.*, spaces which do not admit of complete revolutions of the holder—is the object of this invention; and I have accomplished this by combining with the tool-socket a system of ratchets, whereby the tool may be rotated continuously in one direction, although the holder is vibrated, or oscillated according to the space afforded.

To enable others to make and use this invention, I shall now proceed to describe its construction and operation.

In the accompanying drawings, Figure 1 is an elevation of a bit-stock made in accordance with this my invention. Fig. 2 is an elevation of a part of the same detached; and Figs. 3 and 4 are sectional views of the ratchet-box dismembered, Fig. 3 being the upper part and Fig. 4 the lower portion or the tool-socket of the bit-stock.

In the said figures similar letters denote similar parts.

A is the tool-socket provided with a hole of a quadrangular or square sectional area expanding toward the under side, and having a spring lever or catch, B, pivoted at b, to be operated from the outside at a. The internally-projecting hook C, penetrating a corresponding recess in the tool shank, firmly locks it. This part of the bit-stock is similar in construction to others in use, and the improvement subject of this patent does not relate thereto. On top of this socket is fitted a box

which is provided on top and bottom with ratchet-teeth d d', arranged to operate in opposite directions. Within this box there is a circular double ratchet plate, G, the teeth of which mesh in with either the upper or lower ratchet-teeth of the box, at the option of the operator. The double ratchet-plate is maintained in position with respect to the axis of the implement by means of a spindle, S, projecting on top and bottom, so as to fit corresponding orifices through the top and bottom part of said box. The upper spindle may be continued to the outside of the socket and may be shaped into a crank, or it may terminate in a shank, T, which in its turn may fit a socket formed in the lower end of the crank. The depth of the box is made to exceed the thickness of the double ratchet plate by at least the depth of the teeth. The double ratchet-plate, which is fast on the spindle S, is thus capable of a limited up-and-down play within the box.

The operation of this device is as follows: Supposing the parts to be adjusted for work—that is to say, the tool to be inserted in the socket A and the crank to be mounted on the shank T, and rotary motion to be imparted to the latter—the lower ratchet-teeth of the plate G will mesh in with the ratchet-teeth d', and thus cause the bit to partake of the movement of the crank. If the whole revolution cannot be completed for want of space surrounding the crank, then the crank is oscillated or vibrated back and forth, every back movement causing the ratchet plate G to ride over the ratchet teeth d', but taking hold of the bit-socket to be carried forward by the advance or forward movement of the crank. In this way it will be understood that by vibrating the lever or crank the distance of the length of one or more teeth the bit will be rotated continuously in one and the same direction. In order to withdraw the bit from after it shall have performed its work in the wood it is only necessary to draw the plate up in contact with the ratchet-teeth d on the upper part of the box D and to cause the ratchet-teeth to bear with but slight pressure against it. In this way the rotary motion of the bit may be reversed by continuing the same vibratory action of the crank.

scribed.
2. In combination with a tool socket of otherwise ordinary or suitable construction, the employment of a right and left hand ratchet-box, together with a circular double ratchet-plate, under the arrangement described, so that the said ratchet-plate may be brought into working contact with either

right or to the left, as the case may be.
In testimony whereof I have signed my name to this specification before two subscribing witnesses.

LOUIS C. BODIER.
